UNITED STATES PATENT OFFICE

ALFRED GLYNNE LOBLEY, OF CHAPEL-EN-LE-FRITH, ENGLAND, ASSIGNEE TO BIRMINGHAM ELECTRIC FURNACES LIMITED, OF BIRMINGHAM, ENGLAND, A CORPORATION OF GREAT BRITAIN

ELECTRICAL SWITCH

Application filed September 22, 1926, Serial No. 136,964, and in Great Britain October 1, 1925.

This invention has reference to electrical switches of the quick-make and quick-brake type wherein a spring element is interposed between a lever or similar operating member 5 and a trip-action member that carries or is connected with the movable contact member, and wherein the displacement of the said operating member through a predetermined distance (either in the "break" or the "make" 10 direction) so shifts the spring element in relation to the pivot centre of the trip member as to render the said spring effective for opening or closing the switch with a snap action.

When such switches are used for certain 15 purposes (as, for example, when the operating lever is actuated mechanically or by a thermostat device) the said lever may be subjected to intermittent or other impulses tending to oscillate or displace the snap-action 20 spring without actually carrying the latter over the dead centre of the system, and when such oscillations are set up as the lever is approaching the tripping point, they may, unless their effect be neutralized, result in slight 25 separations of the switch contacts sufficient to permit of arcing between the latter and irregularity or intermittence in the circuit controlled by the switch.

In order to eliminate the possibility of arcing 30 and intermittence occurring under the conditions referred to, and with the further object of providing an efficient quick make-and-break switch which is specially adapted for thermostatic or mechanical actuation, it 35 is proposed, according to the present invention, to arrange in connection with the spring-actuated trip member, means for positively retaining or locking the said member definitely in either its "on" or its "off" position, and 40 to utilize the operating lever (or means connected therewith) for releasing the trip member only when the snap-action spring has been carried beyond the dead-centre point or made effective for imparting the full break or make 45 movement to the trip member.

A form of switch constructed according to the said invention, and embodying provision for neutralizing or damping-out the effect of lever and spring oscillations when the said 50 lever is in proximity to the dead centre of the

system, is shown in the accompanying drawings in which

Figure 1 is a general elevation of the switch mechanism which is adapted to be operated, in the break direction, by a thermostat (part 55 of which is also shown in the figure) and in the other or make direction by a spring. This view shows the parts in the positions they assume when the switch-contacts or terminals are closed but with the operating lever just on the point of being tripped in the circuit-breaking direction by the thermostat control. 60

Figure 2 shows certain parts of the switch in plan or edge view, on a larger scale than Figure 1. 65

Figure 3 is a view of the switch similar to Figure 1 showing the parts in the "off" or circuit-breaking positions, and

Figure 4 shows the switch closed and with the member that controls the contacts definitely locked in the "on" position. 70

The same letters of reference indicate corresponding parts in the several figures of the drawings.

In this switch, the trip member (i. e., the 75 member which actually controls the separation and closing of the contacts a , a') consists of a pair of elongated plates or crank arms b , b' furnished with bearings b^2 for suitably-bracketed pivots and separated sufficiently to 80 permit of an extremity of an operating lever c being extended into the space between them. The trip-spring element d (which may be a simple tension spring or a pull-action compression spring) is connected at one end to 85 the extremity c' of the lever and at the other end to a cross-pin b^3 or other anchorage disposed between the plates of the trip member and forms an extensible link connection between the trip and lever, whilst the pivots b^4 90 of the said trip-member are disposed intermediate the respective connections of the spring with the lever and trip member, or in such a manner as will enable the lever, during its angular displacement in either direction, 95 to first increase the tension of said spring and then bring about the snap action of the trip member by carrying the spring past or over the centre of the trip-member pivots.

A suitable stop or catch is embodied in the 100

switch for limiting the movement of the trip member in both the make and break directions, whilst the trip member is connected, directly or indirectly in any convenient manner, with the movable contact member of the switch. As an example of contact arrangement which may be used with advantage in a thermostat-operated switch for controlling a relay circuit, two contacts a , a^1 of stud-like form are used and one of these is carried on a fixed terminal support a^2 whilst the other is carried by a spring blade a^3 whose shank is fixed to another terminal support a^4 , this spring being extended into engagement or connection with a piece of ebonite or other non-conductor a^5 fixed to and extending from one side of the trip member. The tendency of the blade spring is to maintain the studs in close contact both when the trip member is in the "on" position and at or during commencement of the break action, but on the trip-member being shifted to the "off" position, the contact stud on the spring contact arm is moved away from the fixed contact to a distance sufficient to prevent arcing between the contact studs when the switch is open.

To provide for the definite locking of the trip-member and its associated contact member in both the "on" and "off" positions, two pawl-like devices e , e^1 , are used and disposed on opposite sides of, and in the plane of movement of, the operating lever. These pawls may consist, as shown, of spring blades or tongues stiffened intermediate their two end portions by riveting light but rigid metal plates e^2 thereto, and one end of each pawl is anchored to a post e^3 or similar attachment on the switch base, whilst the other ends e^4 , e^5 are adapted respectively to engage suitably-disposed notches or shoulders e^6 , e^7 , formed on the opposite edges of one of the trip-member plates. These pawls and notches are so disposed that when the trip-member is in the "on" position (Figure 4) it is locked by the end e^4 of the pawl e so engaging the notch e^6 as to resist any force tending to shift the said trip-member towards the "off" position, whereas in the open position of the said member, it is similarly engaged and locked by the end e^5 of the other pawl e^1 engaging the notch e^7 (see Figure 3), whilst for liberating the trip member when (but not until the snap-action spring d has been shifted over the centre of the trip-member pivot and made definitely operative for opening or closing the switch) the operating lever is provided with a pair of adjustable screws or abutments d , d^1 respectively projecting from its opposite edges towards the pawls e , e^1 ; the arrangement being such that as the lever swings over the dead-centre point and brings the spring d into effective action, one of the abutments will impinge upon and disengage the pawl that is locking the trip-member and liberate the lat-

ter to permit of the opening or closing (as the case may be) of the switch.

The operating lever and a switch such as above described may be actuated positively (by mechanical, thermostatic or other means) 70 in both the make and break directions, or have positive actuation in one direction only, the movement in the other direction being derived from a suitably-applied spring. In the arrangement illustrated, however, where 75 the switch is part of an installation for automatically controlling or regulating the supply of current to electric furnaces, the opening of the switch is effected positively by the impingement of a thermostat-operated 80 contact g on the short heel c^1 of the switch lever, whilst the closing movement is derived from a spring h which (on sufficient retraction of the thermostat contact) throws the lever in the appropriate direction for rendering the trip-spring operative and disengaging the retaining pawl so that the trip-member may be actuated for closing the switch contacts.

A stop device is incorporated in the switch 90 for limiting or determining the movement of the trip-member in both directions, and in the illustrated construction, the stop is constituted by two horns or projections i , i^1 , co-operating with a plate i^2 fixed to the switch- 95 base. Figures 3 and 4 show how the stop-plate arrests the trip respectively in the "off" and "on" positions.

Having described my invention, what I claim and desire to secure by Letters Patent 100 is:—

1. A snap switch having a pivoted trip member, a pivoted actuating lever, a spring fixedly connected to the trip member and lever, the axis about which the trip member swings being located between the lever pivot and the point of connection between the spring and trip, the arrangement being such that the path of movement of the both ends of the spring and the portions of the lever and trip to which the spring is connected from one position to the other is across the pivot of the trip member, a switch member connected to the trip, latches for locking the trip in its extreme positions, and means for disengaging the latches.

2. A snap switch having a pivoted trip member, a pivoted actuating lever, a tension spring fixedly connected to the lever and trip and at points remote from their pivotal connections, said spring extending in the general direction of the lever, the pivot for the trip being located between the point at which the spring is connected to the trip and the lever pivot, a switch member arranged to be actuated by the trip, trip locking latches, and means for disengaging the latches when the lever is moved from one position towards its other position.

3. A snap switch comprising a trip hav- 130

ing a pair of crank arms, a crank pin connecting the arms to each other, pivotal supports for the crank arms, a switch member connected to the trip, latches for holding the trip in its extreme positions, a pivoted lever extending between the cranks of the trip, and a spring fixedly connected to the lever and the crank pin located between the cranks, said spring forming an extensible link connection between the trip and the lever.

10 4. A snap switch comprising a trip having a pair of crank arms, a crank pin connecting the arms to each other, pivotal supports for the crank arms, a switch member connected to the trip, latches for holding the trip in its extreme positions, limit stops on the trip, a pivoted lever extending between the cranks of the trip, and a spring fixedly connected to the lever and the crank pin located between the cranks, said spring forming an extensible link connection between the trip and the lever.

15 5. A snap switch having a pivoted trip, limit stops on the trip, means for actuating the trip from one extreme position to its other extreme position, a fixed contact, a leaf spring fixed against movement at one end and connected to the trip at its other end, and a movable contact carried by the leaf spring between its ends, and adapted to engage the fixed contact when the trip is in one of its extreme positions.

20 In testimony whereof I have hereunto set my hand.

25 35 ALFRED GLYNNE LOBLEY.
